Des. 203,125
Patented Dec. 7, 1965

203,125

WEED CUTTER

Louis Gouveia, Rte. 1, Box 582, Grass Valley, Calif.

Filed May 24, 1965, Ser. No. 85,430

Term of patent 14 years

(Cl. D39—1)

I claim:

The ornamental design for a weed cutter, as shown and described.
